Specification of Letters Patent.

Patented Jan. 11, 1916.

Application filed December 27, 1912. Serial No. 738,816.

To all whom it may concern:

Be it known that we, SWAN SMITH and OSCAR W. HAMMERQUIST, citizens of the United States, residing at Ramsey county, 5 in the State of Minnesota, have invented new and useful Improvements in Printing-Presses, of which the following is a specification.

Our invention relates to improvements in 10 printing presses of the cylinder type. Its object is to provide a simple and durable high-speed press having a horizontally reciprocating impression cylinder and a horizontally and vertically reciprocating bed 15 adapted to co-act with said cylinder.

A further object is to provide in a printing press of this class means for dropping the bed at will, irrespective of the movement or position of the impression cylinder 20 and for automatically retaining said bed in lowered position when the feeding of the press is discontinued.

A further object is to provide in a press of this kind, a power-driven reciprocatory 25 and continuously revoluble impression cylinder, and means for insuring perfect registration between said impression cylinder and the bed of the press.

In the drawings Figure 1 is a side elevation 30 of our improved press; Fig. 2 is an end elevation of the same with the feeding table removed and a part of the frame broken away; Fig. 3 is a sectional view taken on the line 3—3 of Fig. 2; Fig. 4 is a detail sectional view showing the cylinder and bed, with mechanism for reciprocating the latter vertically; Fig. 5 is a detail side elevation illustrating the mechanism for automatically retaining the bed in lowered position, and Fig. 6 is a plan view of the same.

Referring to the drawings, we have used the reference numeral 9 to indicate the press frame, 10 the impression cylinder, 11 the bed which is adapted to receive the ordinary printing form, 12 the feeding table, and 13 the delivery platform.

The impression cylinder 10 is provided with a supporting shaft 14, journaled at its ends in the carriage blocks 15, which are movable in the guides 16 of the frame 9.

The bed 11 is movable horizontally on the

supporting slides 17, which will be herein-after more fully described. Mechanism for reciprocating the cylinder and bed, and for holding the same a predetermined period at 55 the ends of their strokes, is provided as follows: The cam shaft 18, in the frame 9, carries a double-faced cam 19, and is operatively connected through the gear wheels 20 and 21 with the combined power pulley 60 and balance wheel 22. A segment 23, provided at each end with a cam roller 24, is fixed to the rock shaft 25 on the frame 9. Each face of the double cam 19 engages a roller 24 and when rotated rocks the shaft 65 25 backward and forward. Levers 26, extending upwardly from the shaft 25, are pivotally attached to a connecting rod 27. These rods pass on either side of the cylinder 10 and are pivotally connected with the 70 carriage blocks 15. An arm 29 on the segment 23 is connected through the link 30, bell-crank 31 and adjustable rod 32, with the bed 11. As the segment 23 is shifted to move the cylinder 10, said arm 29 operates through said link, crank and rod to move the bed in a direction opposite to that of the cylinder and at substantially the same speed. The faces of the cam 19 are angularly spaced, each comprising a neutral low surface, an active outwardly extending surface, a neutral high surface, and an inwardly extending surface. The active surfaces cause uniform strokes of the cylinder 10 and bed 11 and the neutral surfaces 80 retain said cylinder and bed for a predetermined interval at the end of their strokes. The cylinder 10 is driven continuously in one direction by the gear wheel 33 on the cylinder supporting shaft 14 through 90 the idle gear 34, which meshes with the driving gear 20 on the cam shaft 18. This idle gear 34 is supported in position and secured in mesh with the gears 33 and 20, by means of the links 35 and 36, which 95 extend respectively to the shafts 14 and 18 and form a folding support between said shafts. These links move the idle gear 34 and compensate for the change in position of the gear 33, as the cylinder 10 moves forward and backward.

The gearing for rotating the cylinder is

timed with respect to the horizontal movement of the cylinder and bed to register said cylinder with a printing form contained within the bed. The wearing of 5 parts, which might otherwise render this registration imperfect, is overcome by a gear wheel 37, formed on the cylinder 10, and arranged to mesh with the rack 38 on the bed 11, when said bed is in contact with 10 the cylinder. Further adjustment to take up wear in said gear 37 and rack 38 is provided in the rod 32, above described, which is adjustable to change the relative position of said cylinder and bed, thereby securing 15 perfect mesh between said gear and rack on the printing stroke of the cylinder.

The bed 11 is slidable vertically between the guide plates 39 and horizontally on the supporting slides 17. These slides are reciprocated vertically to normally elevate the bed when the cylinder moves forward, thus causing said cylinder to bear against the form contained in said bed and to lower the bed to prevent contact between said form 20 and cylinder as the latter moves back. Each end of the slides 17 is supported upon a standard 40 adjustably secured thereto, said standards being mounted at their lower ends upon the movable beams or bases 41. 25 Each base consists of a channel bar 42 having a bearing upon a pair of eccentric blocks 43 slidable within the channel of said bar and mounted upon the eccentric shafts 44. These shafts are revoluble in the frame and 30 are each provided with an arm 45, said arms being connected by a link 46 adapted to synchronize the movements thereof. One of these arms is connected through a second link 47 with the pivotally suspended lever 48, on the frame 9, which is joined by the 35 bar 49 with the cam lever 50. This cam lever is pivotally mounted at one end on the frame and is supplied with the cam roller 51 arranged in engagement with the inside 40 cam 52 on the cam shaft 18. Said cam lever is intermittently oscillated by said cam, this movement being transmitted through said bar 49, lever 48, links 46 and 47, and arms 45, to rock the eccentric shafts 44, thus raising 45 the bed to and from printing position. The cam 52 is designed and positioned on the shaft 18 to raise the bed on the printing stroke of the cylinder and to lower said bed during the return stroke of said cylinder. 50 The guide pins 53 on the frame 9, extend 55 through perforations in the slides 17 and retain said slides in their vertical paths.

A printing form within the bed 11 is supplied with ink by the form rollers 54 on the carriage blocks 15. These rollers are furnished with ink by engagement with the inking plate 55 on the bed 11, only when said bed is raised to printing position. Ink is distributed to said inking plate in any 60 ordinary manner not shown.

During the operation of the printing press, it is often desirable to prevent contact between the bed and impression cylinder during one or more strokes of the latter or to discontinue such contact at any point 70 in the printing stroke. We have provided foot-operated means whereby the bed may be instantly lowered, also automatically operated means connected with said foot-operated means, whereby the elevation of the 75 bed is prevented upon failure to feed a sheet of paper to the cylinder. The foot-operated means consist of a lever 56, mounted on the revoluble shaft 57, in the frame 9, said lever being provided with a roller 58 at its end. 80 This lever is normally held by the spring 59 in position adjacent to the extended end of the bar 49 above described. The connection between the bar 49 and the cam lever 50 is formed by a pin 60, in said lever, adapted to engage the notch 61 in said bar. Operation of the foot-lever raises the bar 49 and disengages the same from the pin 60, thus disconnecting said bar and lever and permitting the spring 62 between the lever 85 90 95 100 105 110 115 120 out of the path of the trip bar 78 on the carriage blocks 15. In case a sheet of paper is omitted from the table, the roller 65 is carried into the perforation 79 in said table, 5 thus permitting further rotation of the shaft and movement of the trip rod 70 into the path of said trip bar 78. The cam 80 on the cylinder supporting shaft 14 is designed to raise this trip bar 78 during the rotation 10 of said cylinder from feeding to printing position, while the same rests in its reciprocatory path. The elevation of said trip bar, by said cam, lifts the trip rod 70, which operates through the lever 72, shaft 57 and 15 foot-lever 56, to disengage the bar 49 from the cam lever 50, thus preventing the elevation of the bed on the printing stroke of the cylinder.

In operation, sheets of paper are successively fed to the impression cylinder 10 which is provided with grips 81 and the ordinary associated operating mechanism not shown. This cylinder passes over the bed 12 which advances to meet it and is 20 adapted to deliver the printed sheets to any ordinary delivery mechanism, not shown. The bed 11 is normally elevated on the forward stroke of the impression cylinder 10 to cause the printing form within said bed 25 to bear against said cylinder, and is lowered on the return stroke of the cylinder to prevent such contact. In case the feeding of the press is discontinued, the bed is automatically retained in its lowered position, 30 but may be instantly lowered from its printing position by operating the foot-lever 56.

This improvement in printing presses is particularly advantageous in that the length of the stroke of the cylinder is reduced one- 40 half by synchronizing therewith a similar stroke of the bed. Contact between the impression cylinder and printing form in the bed, may be automatically prevented or manually and instantly discontinued. The 45 inking operation is automatically discontinued with the dropping of the bed. The stroke is uniform and the reciprocation of the cylinder and bed is intermittent to allow ample time for feeding and delivery. 50 Perfect registry of a reciprocating bed with a continuously revolute and reciprocating cylinder is secured during the printing stroke of the cylinder and bed, and is maintained by convenient adjustment if its parts 55 become worn.

What we claim as new and desire to protect by Letters Patent, is:

1. In a printing press, the combination of a frame, a bed on said frame, an impression cylinder for said bed, mechanism for intermittently engaging said bed and cylinder, means for continuously rotating said cylinder and separate means for reciprocating said cylinder and bed in straight paths 60 in opposite directions and for holding the

cylinder at the beginning and end of the printing stroke, whereby during the pause in reciprocation at the beginning of a stroke, a sheet may be fed to the cylinder while rotating and carried a substantial distance 70 to printing position and during the pause in reciprocation at the end of a stroke, the sheet may be withdrawn from printing position and ejected from the press by said rotating cylinder. 75

2. In a printing press, the combination of a frame, a bed on said frame, an impression cylinder for said bed, continuously power-driven means for constantly rotating said cylinder and a power-driven cam in operative connection with said cylinder and bed having active surfaces adapted to intermittently reciprocate the cylinder and bed in opposite directions, one stroke of the cylinder being at a rate equal to the peripheral 80 movement of said cylinder on said bed, whereby perfect registry between the cylinder and bed is obtained. 85

3. In a printing press, the combination of a frame, an impression cylinder revolute and slideable on the frame, a bed on the frame, means for engaging the bed with said cylinder on its forward stroke, a power shaft revolute in the frame, a train of gears in operative connection with said cylinder and shaft, a cam on said shaft in operative connection with said cylinder and bed, said cam having active surfaces adapted to reciprocate the cylinder and bed in opposite directions at speeds proportionate to the peripheral movement of said cylinder, whereby perfect 90 registry between the cylinder and bed is obtained. 95

4. In a printing press, the combination of a frame, an impression cylinder on the frame, a bed movable on said frame, means for intermittently reciprocating said bed and cylinder horizontally in opposite directions, power operated mechanism for normally elevating the bed during the forward stroke of the cylinder and for lowering said bed during the return of said cylinder and foot-operated means for rendering said mechanism inoperative. 105

5. In a printing press, the combination of a frame, an impression cylinder on the frame, a bed movable on said frame, means for intermittently reciprocating said bed and cylinder horizontally in opposite directions, power operated mechanism for normally elevating the bed during the forward stroke of the cylinder and for lowering said bed during the return of said cylinder, foot-operated means and automatically actuated means for rendering said mechanism inoperative. 110

6. In a printing press, the combination of a frame, a bed on said frame, an impression cylinder for said bed, a cam in operative connection with said cylinder and bed for 115 120 125 130

reciprocating the same horizontally in opposite directions and synchronizing the movements thereof and means for continuously revolving said cylinder, said cam being adapted to move said cylinder and bed coördinately with the rotation of the cylinder to register said cylinder with said bed.

7. In a printing press, the combination of a frame, a bed on said frame, an impression cylinder for said bed, a cam in operative connection with said cylinder and bed for intermittently reciprocating the same horizontally in opposite directions and synchronizing the movements thereof and gearing in operative connection with said cam for continuously revolving said cylinder, said cam being adapted to move the cylinder and bed coördinately with the rotation of the former to register said cylinder with said bed and to hold the cylinder at the ends of its strokes, whereby the same may be fed and turned to printing position and revolved from printing to delivery position.

8. In a printing press, the combination of a frame, a bed on said frame, an impression cylinder for said bed, power-driven means for continuously revolving said cylinder, means for intermittently reciprocating said cylinder and bed horizontally in opposite directions and synchronizing the movements thereof, said means being adapted to move the cylinder and bed coördinately with the rotation of the former to register said cylinder and bed, means for raising the bed to engage the same with said cylinder on its forward stroke and for lowering the bed to prevent such engagement on the return of said cylinder.

9. In a printing press, the combination of a frame, a bed and an impression cylinder therefor, movable upon said frame, means for continuously rotating the cylinder, means for reciprocating said cylinder and bed horizontally in opposite directions and coördinately with the rotation of the former, to register said cylinder and bed, and means for normally reciprocating the bed vertically and for correlating its vertical movement with respect to the reciprocation of said cylinder.

10. In a printing press, the combination of a frame, a bed and an impression cylinder therefor, movable upon said frame, means for continuously rotating the cylinder, means for reciprocating said cylinder and bed horizontally in opposite directions to synchronize their movements with the rotation of the cylinder and register said cylinder and bed, mechanism for normally reciprocating the bed vertically and for correlating its vertical movement with respect to the reciprocation of said cylinder and foot-operated means for rendering said mechanism inoperative.

11. In a printing press, the combination

of a frame, a bed and an impression cylinder movable upon said frame, means for continuously rotating the cylinder, means for reciprocating said cylinder and bed horizontally in opposite directions, means for intermittently raising the bed into coöperation with said cylinder and correlating its vertical movement with respect to the reciprocation of said cylinder, and automatically operated mechanism to disconnect said last mentioned means and thereby retain the bed in lowered position, said mechanism being rendered inoperative by the presence of a sheet of paper in position to be fed to said cylinder.

12. In a printing press, the combination of a frame, a continuously revoluble impression cylinder on said frame, a bed on the frame, a power-driven cam in operative connection with said cylinder and bed for intermittently reciprocating the same in opposite directions, said cam having active surfaces to move the bed and cylinder and neutral circular surfaces to check and hold said cylinder and bed against reciprocation a brief period at the ends of their strokes.

13. In a printing press, the combination of a frame, a bed on the frame, an impression cylinder for said bed, means for intermittently reciprocating said cylinder and bed in opposite directions, a power driven shaft parallel with said cylinder and a train of spur gear wheels, including a floating idler wheel, operatively connecting said shaft with said cylinder for continuously rotatting the latter.

14. In a printing press, the combination of a frame, a bed and an impression cylinder therefor movable on said frame, means for reciprocating said cylinder and bed on the frame, a power driven shaft, a gear on said shaft, a gear on said cylinder, a pair of pivotally connected links, one of said links being attached to said cylinder and the other to said power driven shaft, and an idle gear revolvably mounted at the joint between said links and arranged to mesh with said first mentioned gears.

15. In a printing press, the combination of a frame, a bed and an impression cylinder therefor, movable on said frame, means for intermittently reciprocating said cylinder and bed, means for continuously rotating said cylinder, a gear on the cylinder, a rack on said bed, means for raising the bed and meshing said gear with said rack during one stroke of the cylinder and for lowering the bed to prevent the meshing of said rack with said gear during the return stroke of said cylinder.

16. In a printing press, the combination of a frame, carriage blocks slidable on said frame, a cylinder supporting shaft journaled in said blocks, a gear on said shaft, an impression cylinder mounted on the shaft, a

- bed movable upon the frame, means for intermittently reciprocating said cylinder and bed, a power shaft on the frame, a gear on said shaft, a link attached at one end to 5 said cylinder supporting shaft, a second link attached at one end to said power shaft, a journal pivotally connecting the free ends of said links, and an idle gear revoluble on said journal and arranged to mesh with the above mentioned gears.
17. In a printing press, the combination of a frame, a bed on the frame, an impression cylinder for said bed, means for reciprocating said cylinder on said frame, a gear wheel for rotating the cylinder, a power shaft in the frame, a gear wheel on said shaft, a folding support between said cylinder and shaft, and an idle gear journaled on 15 said support and retained thereby in mesh with the above mentioned gears.
18. In a printing press, the combination of a frame, a feeding table therefor, a bed on the frame, an impression cylinder for said bed, mechanism for raising and lowering the bed, foot-operated means for rendering said mechanism inoperative and causing said bed to remain in lowered position, tripping devices operatively connected with said foot-operated means, a spring actuated arm 20 in operative connection with said tripping devices and adapted to rest upon a sheet of paper when fed from said table to said cylinder, said arm in the absence of a sheet being adapted to tilt and trip said devices 25 so as to lower the bed.
19. In a printing press, the combination of a frame, an impression cylinder on the frame, beams on the frame, means for reciprocating said beams vertically, horizontal 30 supporting slides, standards threaded and adjustable at their lower ends in said beams and at their upper ends in said slides, a bed on said slides and means for reciprocating the cylinder and bed horizontally in opposite 35 directions.
20. In a printing press, the combination of a frame, an impression cylinder slideable on said frame, a power driven cam shaft on the frame, a cam on said shaft, a rock 40 shaft on the frame, a segment on said shaft in operative connection with said cam, levers on said rock shaft, rods pivotally connecting said levers with said cylinder, a bed slideable on said frame, a bell crank on said frame, 45 a link pivotally connecting said segment with one arm of said crank, and a rod pivotally connecting the other arm of said crank with said bed.
21. In a printing press, the combination 50 of a frame, an impression cylinder slideable on said frame, a power driven cam shaft on the frame, a cam on said shaft, a rock shaft on the frame, a segment on said rock shaft in operative connection with said cam, levers 55 on said rock shaft, rods pivotally connecting said levers with said cylinder, a bed slideable on said frame, a bell crank on said frame, a link pivotally connecting said segment with one arm of said crank, and a rod pivotally connecting the other arm of said crank with said bed.
22. In a printing press, the combination 60 of a frame, an impression cylinder revoluble in and slidably mounted on said frame, a bed, horizontal slides for said bed, means for intermittently reciprocating said cylinder and bed horizontally, mechanism for intermittently reciprocating said slides to normally raise and lower said bed, and correlate its vertical movement with respect to the movement of the cylinder, and foot-operated means for rendering said mechanism inoperative and to instantly lower the bed.
23. In a printing press, the combination 65 of a frame, an impression cylinder revoluble in and slidably mounted on said frame, a bed, horizontal slides for said bed, means for intermittently reciprocating said cylinder and bed horizontally, mechanism for intermittently reciprocating said slides to normally raise and lower said bed, and correlate its vertical movement with respect to the movement of the cylinder, and automatically operated means for rendering said mechanism inoperative to retain said bed in lowered 70 position.
24. In a printing press, the combination 75 of a frame, a cylinder revoluble in and slideable on said frame, eccentric shafts on the frame, a bed, horizontal slides for said bed supported on said shafts, means for intermittently reciprocating said cylinder and bed horizontally, and means for simultaneously turning said eccentric shafts to 80 raise and lower the bed.
25. In a printing press, the combination 85 of a frame, a cylinder revoluble in and slideable on said frame, eccentric shafts on the frame, a bed, horizontal slides for said bed, said slides being supported on said shafts and adjustable with respect thereto, means for intermittently reciprocating said cylinder and bed horizontally, and means for simultaneously turning said eccentric shafts to 90 raise and lower the bed.
26. In a printing press, the combination 95 of a frame, a cylinder revoluble in and slideable on said frame, eccentric shafts on the frame, a bed, horizontal slides for said bed, said slides being supported on said shafts and adjustable with respect thereto, vertical guides for said slides, means for intermittently reciprocating said cylinder and bed horizontally and means for simultaneously turning said eccentric shafts to raise and lower the bed.
27. In a printing press, the combination 100 of a frame, an impression cylinder revoluble in and slidably mounted on said frame, 105

centric shafts journaled in the frame, connecting means between the shafts, a bed, horizontal slides for said bed, said slides being mounted on said shafts and adjustable with respect thereto, means for reciprocating said cylinder and bed horizontally, a power shaft on the frame, a cam on said shaft, a cam lever pivoted at one end on the frame and in operative connection with said cam, said lever being operatively connected with one of said shafts for turning the same to raise and lower said bed.

28. In a printing press, the combination of a frame, a cylinder revoluble in and slideable on said frame, eccentric shafts on the frame, a bed, horizontal slides for said bed, bases carried on said shafts, standards mounted on said bases and adjustably attached at their upper ends to said slides, means for intermittently reciprocating said cylinder and bed horizontally and means for simultaneously turning said eccentric shafts to raise and lower the bed.

29. In a printing press, the combination of a frame, a cylinder revoluble in and slideable on said frame, eccentric shafts on the frame, a bed, horizontal slides for said bed, eccentric blocks on said shafts, bases slideable on and supported by said blocks, standards mounted on said bases and adjustably attached at their upper ends to said slides, means for intermittently reciprocating said cylinder and bed horizontally, and means for simultaneously turning said eccentric shafts to raise and lower the bed.

30. In a printing press, the combination of a frame, an impression cylinder revoluble in and slidably mounted on said frame, eccentric shafts on the frame, a bed, horizontal slides for said bed, said slides being supported on said shafts, means for reciprocating said cylinder and bed horizontally, connecting means between the shafts, a bar in operative connection with one of said shafts and formed with a socket therein, a power shaft on the frame, a cam on said shaft, a cam lever pivoted at one end on the frame and in operative connection with said cam, said lever being provided at its lower end with a pin, which is adapted to normally rest in said socket and form a connection between said bar and lever whereby upon movement of said cam lever the shafts are turned and the bed raised and lowered.

31. In a printing press, the combination of a frame, an impression cylinder revoluble in and slidably mounted on said frame, eccentric shafts on the frame, a bed, horizontal slides for said bed, said slides being supported on said shafts, means for reciprocating said cylinder and bed horizontally, connecting means between the shafts, a bar in operative connection with one of said shafts and formed with a socket therein, a power shaft on the frame, a cam on said shaft, a

cam lever pivoted at one end on the frame and in operative connection with said cam, said lever being provided at its lower end with a pin, which is adapted to normally rest in said socket and form a connection between said bar and lever whereby upon movement of said cam lever the shafts are turned and the bed raised and lowered, resilient means tending to turn said shafts and lower the bed, and a foot lever on the frame adapted to raise said bar to disconnect and hold the same from engagement with said lever.

32. In a printing press, the combination of a frame, an impression cylinder revoluble in and slidably mounted on said frame, eccentric shafts on the frame, a bed, horizontal slides for said bed, said slides being supported on said shafts, means for intermittently reciprocating said cylinder and bed horizontally, an arm on each eccentric shaft, a link pivotally attached to said arms to synchronize the movement of said shafts, and means for oscillating said arms to turn said shafts and thereby raise and lower said bed.

33. In a printing press, the combination of a frame, an impression cylinder revoluble in and slidably mounted on said frame, eccentric shafts on the frame, a bed, horizontal slides for said bed, said slides being supported on said shafts, means for reciprocating said cylinder and bed horizontally, connecting means between the shafts, a bar in operative connection with one of said shafts and formed with a socket therein, a power shaft on the frame, a cam on said shaft, a cam lever pivoted at one end on the frame and in operative connection with said cam, said cam lever being provided at its lower end with a pin adapted to normally rest in said socket and form a connection between said bar and lever, whereby upon movement of said cam lever the shafts are turned and the bed raised and lowered, resilient means tending to turn said shafts and lower the bed, a foot lever on the frame adapted to raise said bar to disconnect and hold the same from engagement with said cam lever, and means in operative connection with the foot lever for automatically operating said lever.

34. In a printing press, the combination of a frame having a perforated feeding table thereon, a bed, an impression cylinder therefor, movable on said frame, means for reciprocating said cylinder and bed horizontally in opposite directions, mechanism for normally reciprocating said bed vertically, an arm pivotally mounted on said frame and adapted to drop into the perforation in said feeding table or to rest upon a sheet of paper if one is present on said table, connecting means in operative relation with said mechanism and arm to render said

mechanism inoperative, when said arm drops into said perforation, and cause the bed to remain in lowered position and an operating device carried by said cylinder 5 and adapted to actuate said connecting means.

In testimony whereof, we have signed our

names to this specification in the presence of two subscribing witnesses.

SWAN SMITH.

OSCAR W. HAMMERQUIST.
